(57) **CLAIM**

The ornamental design for a rear combination lamp of motorcycles, as shown and described.

DESCRIPTION

FIG. 1 is a front view of a rear combination lamp for a motorcycle showing our new design.

FIG. 2 is a rear view thereof.

FIG. 3 is a plan view thereof.

FIG. 4 is a bottom view thereof.

FIG. 5 is a right side view thereof.

FIG. 6 is a left side view thereof.

FIG. 7 is a perspective view thereof as seen from the right front side.

FIG. 8 is a perspective view thereof as seen from the left front side.

FIG. 9 is a perspective view thereof as seen from the left rear side.

FIG. 10 is a perspective view thereof as seen from the right rear side; and,

FIG. 11 is a reference view thereof showing its state of use.

The broken line showing of the underneath portion is for illustrative purposes only and forms no part of the claimed design.
